UNITED STATES PATENT OFFICE.

WILBER E. ARNOLD, OF MADISONVILLE, OHIO, ASSIGNOR TO VICTOR SAFE & LOCK COMPANY,
OF CINCINNATI, OHIO, A CORPORATION OF OHIO.

SAFE.

No. 894,932.

Specification of Letters Patent.

Patented Aug. 4, 1908.

Application filed March 30, 1907. Serial No. 365,459.

To all whom it may concern:

Be it known that I, WILBER E. ARNOLD, a citizen of the United States, and residing at Madisonville, Hamilton county, State of Ohio, have invented certain new and useful Improvements in Safes; and I do declare the following to be a clear, full, and exact description of the invention, attention being called to the accompanying drawing, with 10 the reference characters marked thereon, which forms also a part of this specification.

This invention relates to improvements in the construction of safes, the body of which consists of a casting of a non-machineable 15 metal and contains also metal which may be worked by machine-tools. Non-machineable metal is used in order to render such safes secure against attacks by implements which may be used to remove or penetrate 20 the metal. Machineable metal must be used for such parts whereby the door is kept seated in its opening. This is because the complementary parts of safe-door and safe-body which engage each other at that time must 25 be adjusted and tightly fitted to each other, which requires working by tools.

My invention concerns that part of the means whereby the door is kept seated when closed, which is provided on the safe-body 30 and is complementary to a corresponding part on the door, both complementary parts of these means being so fitted that one may receive and engage the other. As shown and described my invention is applied to conditions where a screw-connection is involved in 35 the engagement of the complementary parts of these means and of which connection the male screw is provided on the door, while the female screw is provided on the safe-body 40 and back of the jamb within the opening therein which receives the door. These screw-parts in order to be fitted for proper engagement of their threads, must be worked by machine-tools, and to permit such working, 45 they must accordingly be made out of metal suitable for the purpose.

My present invention concerns the means and manner for holding the workable metal in place which is intended to form that one 50 of the complementary screw-parts which is provided on the safe-body.

In the following specification and particu-

larly pointed out in the claims at the end thereof, will be found a full description of the invention, together with its parts and construction, which latter is also illustrated in the accompanying drawing, in which:—

Figure 1, shows a side-elevation of a safe, parts of it being removed on a sectional line which passes centrally through the door-opening. Fig. 2, shows a side-view of the detached door which is fitted to this opening. Fig. 3, is a cross-section of the safe-body taken on line 3—3, of Fig. 1, and shows the inner side of the front-wall of the safe-body 65 with the door-opening therein. Fig. 4, shows the workable metal-portion provided on the non-workable casting of the safe-body.

The body of the safe is cast of a suitable metal which is of such a nature as to be 70 secure against attacks involving the use of drills or other tools for working metal. It is formed with a substantially cylindrical side-wall A, a closed back-wall B, and the front-wall C, which has the door-opening c. The 75 thickness of this front-wall around the opening may be increased inwardly as shown, to form, if necessary, a more extended jamb D, against which the door E, is seated.

F, F, are the complementary parts of the 80 hinges which are provided on the safe-body. Means are provided whereby this door when closed is kept seated in its jamb and as before stated these means consist of two complementary parts, provided, one on the door and 85 the other on the safe-body, a screw-connection being used whereby these two parts become adapted to engage each other. Of these complementary parts, part G, is the one provided on the door and constitutes the 90 male-screw of the screw-connection. Its thread is fitted to engage a female thread h, contained in a ring H, back of the door-jamb and on the inner side of front-wall C. Both threads must be cut to fit each other, which 95 is done by machine-tools, and requires therefore metal workable in such manner. Accordingly the parts in which these threads are cut consist of a metal which is different from the other metal, but connected thereto 100 and combined with it in a manner so as to form inseparable parts thereof. As to the door, the details of construction and connection of this part G form no part of this inven-

tion. Nor is it important for present purposes whether these threads are cut in this metal before, or after its connection to the other metal.

5 As to the body, ring H, which contains threads h, is made of a metal suitable for working by machine-tools and is held in position by portions of the cast-metal which engage the same, the engagement being obtained by placing this ring into the mold in which the casting of this body is made.

In some of my former patents related to similar subject matter, notably in one issued to me on August 12th, 1902, I show such a ring as being held in place by being embedded around its entire outside into the cast-metal. While this method is entirely satisfactory for the purpose of holding the ring in place, the production of such a composite casting in 20 this manner is connected with difficulties which result frequently in loss of castings. This is by reason of undue strains set up in the contacting metals and of the difficulty in accommodation of one to the other, of the 25 cast-metal while cooling and shrinking and of the rigid ring which is entirely surrounded thereby. This difficulty I overcome by limiting the contact between the two metals, so that the movement of one metal with respect 30 to the other, particularly that of the cast-metal when shrinking during cooling, is not interfered with or opposed by the other. For such purpose I provide for a limited contact only between this ring H, and the cast- 35 metal of the safe-body, such contact being complete only on one side of the ring, viz. its front-side. The ring may thus readily move rearwardly or laterally, or yield to the shrinking strains of the cooling cast-metal, and this 40 latter may readily adjust itself to the ring, so that no opposing strains are set up between the two metals. The ring is held in place by the limited contact of internal, spaced projections P, which extend from the inside of 45 the safe-body and engage the ring in a manner to hold the same against the inside of the front-wall. By preference these projections are arranged at an angle to wall A, from which they extend towards the front-wall, so that 50 ring H, is simultaneously engaged in an axial as well as in a radial direction. The periphery of ring H, which is engaged by these 55 projections is beveled so as to meet them at proper angle as best shown in Fig. 1. These projections are preferably in form of ribs, that is they are entirely free between their ends so as to limit contact with ring H, only to these ends and to avoid accumulation of metal in lumps. This reduces correspondingly 60 the movement which takes place during shrinking and thereby reduces also the danger of cracking, while cooling. A more intimate combination between the two metals is obtained by providing notches p, in the

outside of ring H, into which part of the cast- 65 metal of these ribs may run during the act of casting.

Having described my invention, I claim as new:

1. In a composite safe-structure, the combination of a safe-body of un-machineable metal having a door-opening in its front-wall adapted to receive a door, and spaced integral projections on its inside which extend at an angle towards the front-wall, and a ring of machineable metal provided with means for engaging similar means on the door to hold the same seated and located between said front-wall and the free ends of these projections and held in position by them. 70

2. In a composite safe-structure, the combination of a safe-body of un-machineable metal provided with a door-opening in its front-wall adapted to receive a door, a flat ring of machineable metal fitted against the 75 inner side of the front-wall to surround the door-opening thereat, contact of the ring with said side of the front safe wall being limited to its flat front face only, the inside of the safe-body being provided with spaced 80 projections which engage the ring on its periphery to hold the same in position. 85

3. In a composite safe-structure, the combination of a safe-body of un-machineable metal embodying inclosing walls and provided with a door-opening in its front-wall, a ring of machineable metal limited in its contact with the metal of the safe-body to its flat front side at which it contacts with the inside of the front-wall and the opening in 95 which latter it surrounds, its exposed peripheral outer side being provided with spaced notches, there being also spaced projections which extend from the inner surface of the safe-body and engage the ring on its exposed 100 outside, the metal thereof extending also into the notches of this ring. 105

4. In a composite safe-structure, the combination of a safe-body of un-machineable metal embodying inclosing walls, the front-wall having a circular door-opening, a ring of machineable metal placed with its outer, flat side against the inner side of the front wall so as to be concentric with the opening therein and projecting to the extent of its thickness 110 clear into the safe, and spaced projections extending from the inner surface of the safe-body, which engage said ring to hold it in position against the inside of the front-wall of the safe. 115

5. In a composite safe-structure, the combination of a safe-body of un-machineable metal embodying inclosing walls, the front-wall having a circular door-opening, a ring of machineable metal beveled on its periphery 120 and placed with its flat side against the inner side of the front-wall of the safe so as to be concentric with the opening therein and pro- 125

jecting inwardly from said front-wall to the extent of its thickness, and ribs projecting from the inner surface of the safe-body and engaging with their ends the beveled periphery of the ring to hold the same in position against the inner side of the front-wall of the safe.

In testimony whereof, I hereunto affix my signature in the presence of two witnesses.

WILBER E. ARNOLD.
